UNITED STATES PATENT OFFICE

105,004

DESIGN FOR A COLLAPSIBLE CONTAINER

John H. Fridén, Maplewood, N. J., assignor to
The Sun Tube Corporation, Hillside N. J., a
corporation of New Jersey

Application May 16, 1936, Serial No. 62,676

Term of patent 14 years

To all whom it may concern:

Be it known that I, John H. Fridén, a citizen of the United States, residing at Maplewood, in the county of Essex and State of New Jersey, have invented a new, original, and ornamental Design for a Collapsible Container, of which the following is a specification, reference being had to the accompanying drawing forming a part thereof.

Figure 1 is a perspective view of a collapsible container embodying my new design as seen from one side;

Figure 2 is a similar view of the container as seen from the front, and

Figure 3 is a top plan view of the container.

The design is characterized by a slender, cylindrical stem at the top of the container projecting from a central, circular, flattened portion surrounded by a gently sloping, frusto-conical shoulder, the body of the container extending along smooth, unbroken lines from the outer, circular edge of said shoulder to a substantially straight line edge at the bottom, the several elements comprising said design being in the relation, configuration, and proportion shown.

I claim:

The ornamental design for a collapsible container, as shown and described.

JOHN H. FRIDÉN.
